Claims priority, application Sweden Feb. 25, 1974

Term of patent 14 years

Int. Cl. D23—04

U.S. Cl. D23—163

FIG.1

FIG. 7

FIG. 5

FIG. 6

FIG. 3

FIG. 4

FIG. 2

FIG. 1 is a front perspective view of a nozzle for ventilating air embodying our new design;

FIG. 2 is a front elevational view thereof;

FIG. 3 is a rear elevational view thereof;

FIG. 4 is a side elevational view taken from the left of FIG. 2;

FIG. 5 is a side elevational view taken from the right of FIG. 2;

FIG. 6 is a top plan view thereof; and

FIG. 7 is an inverted plan view thereof.

FIGS. 2-7 are shown in reduced scale for ease of illustration.

We claim:

The ornamental design for a nozzle for ventilating air, substantially as shown and described.
